EDWARD FREUND, OF LONG BEACH, NEW YORK

SOUND REPRODUCER

Application filed April 12, 1929. Serial No. 354,537.

My invention relates to the class of sound reproducer employed as a loud speaker for radio receiving sets, and also as the sound reproducer for phonographs operating with electric reproducers or "pick-ups".

The object of my invention is to improve the type of loud speaker wherein a woven fabric is utilized as the vibrating body or diaphragm for reproducing the sound, and especially the type of speaker wherein two such diaphragms are drawn together at the center and at which point the connecting link from the armature of the electro-magnetic speaker unit is attached; and more particularly my invention relates to the method of stretching the fabric diaphragms.

In carrying my invention into effect I provide two fabric diaphragms made from sheets, preferably one larger than the other, joined at the center, and stretched between suitable frames which are held rigidly spaced so as to form two cones, one of greater depth than the other, and an electro-magnetic vibrator which is connected to the diaphragms at the apexes of the two cones where they are joined together. I also provide means for adjusting the tension of the diaphragms, such means being preferably the same means whereby the cone frames are held together.

In carrying out my method of connecting and stretching the diaphragms to form cones, I employ two frames which are connected together by means of tension adjusting means. The fabric sheets are first secured together at the center by perforating the sheets and then binding them together by means of a tubular bolt and clamping washers, or other suitable device, which also serves as the means for attaching the vibrator to the cones. Then the smaller of the two sheets is stretched upon one of the frames, care being taken to stretch the fabric uniformly in all directions and without a wrinkle so as to be perfectly flat. The larger sheet is then drawn over the other frame, care also being taken to draw it uniformly, and in stretching same it is taken up step-by-step around the frame until drawn as taut as possible by hand and without wrinkles. Since the smaller sheet was drawn flat and taut while the larger sheet hung loose, it

will be seen that the larger sheet will immediately assume a cone shape when it is attached to its frame, and that the pull in drawing it taut will create a pull at the center of the smaller sheet and draw it into cone shape. 55 The cone of the smaller sheet, however, will, due to its having been first drawn taut and flat, be quite shallow compared to the cone produced by the larger sheet. The stretching so far is all done by hand, and when the 60 large sheet is fully stretched to the limit by hand, a final stretching is imparted to both cones by adjusting the braces or struts by which the two frames are secured together.

In the accompanying drawing which illustrates my invention, Figure 1 is a perspective schematic view illustrating a pair of cone-shaped diaphragms mounted between a pair of frames adjustably held together; Figure 2 a plan view of the fabric diaphragms before being secured together and before mounting on the frames; Figure 3 an enlarged central cross section illustrating the clamping joint for the fabric sheets and speaker link; Figure 4 an enlarged vertical section showing one of the adjustable struts for the diaphragm frames; Figure 5 a perspective schematic view illustrating the first step in stretching the fabric diaphragms on the frames; Figure 6 a central vertical cross section showing the first stretching of the larger fabric sheet; and Figure 7 an end elevation illustrating the finished state of the device. 75

Referring to the drawings, 1 and 2 indicate rectangular wooden frames, but it will 80 be understood that these frames may be of any other material. The shape of the frame is more important and I employ angular frames in preference to circular frames. 3 and 4 are the small and large fabric sheets, 85 respectively, as shown in Figure 2, and these sheets are secured together at the center as shown at 5. The sheets for this purpose are perforated and the manner of securing them together is shown in Figure 3. The device 6 for securing the sheets together is made like a pin-vise having a shouldered part 7 and a screw-threaded tubular shank 8. The fabric sheets 3 and 4 are placed between washers 9 and 10 and the shank 8 is passed through 90

100

the perforations and the whole clamped against shoulder 7 by nut 11. The connection from the electro-magnetic vibrator is shown at 12 and this rod enters the pin-vise 6 and is clamped in position by adjusting the milled sleeve having the usual internal bevel which engages bevelled clamping jaws formed at the end of shank 8. It will be understood, of course, that rod 12 is part of the electro-magnetic vibrator and is inserted in pin-vise 6 when the vibrator is placed in position.

The electro-magnetic vibrator may be of any desired type or construction and is only conventionally shown in Figures 1 and 7 by its cover or casing 13. The vibrator is preferably mounted on frame 1, or on supports 14 secured thereto, so that the vibrator will be adjacent the shallow cone 3 and hence the rod 12 connecting the vibrator with the cones will be relatively short.

The diaphragm frames 1 and 2 are secured together by four screw-threaded rods 15 which pass through holes in the frames. Frame 2 is locked in position on rods 15 by nuts 16 and 17, and frame 1 is adjustably held on rods 15 by nuts 18 and wing-nuts 19 as shown in detail in Figure 4. To increase the tension of the fabric cones, nuts 18 are retracted and then wing-nuts 19 are each screwed up against the frame, step-by-step to insure even pull on the diaphragms, and when the desired tension is obtained, nuts 18 are screwed down against the frame to lock it in position.

The fabric sheets are secured to the frames by pins or nails 20. These pins are driven through strips 21 which are secured to the frames 1 and 2 with the pin points projecting outward as shown in Figure 4. The fabric sheets of Figure 2 are then placed on the frames as shown in Figure 5, the larger sheet 4 hanging loosely, and sheet 3 being held by four pins at diametrically opposite points 22 (which are marked on the sheets when arranging them for punching the central hole 5) to insure centering the pin-vise 6 within the frames. Sheet 3 is then hooked over the other pins of frame 1. The sheet is then drawn taut by lifting it from one or more adjacent pins, giving a little more stretch to the sheet and rehooking it. This operation is repeated around the entire frame until the desired tension is obtained, and when evenly drawn without wrinkles, pins 21 are bent over as shown in Figure 1, the surplus fabric is trimmed away, and finishing strips of wood 23, Figure 7, are applied to cover the edge of the fabric and the bent over pins. In the operation of drawing the sheet taut I find that the best results are obtained by first slightly taking up the sheet on a few pins next to and on one side of a central point 22, then similarly taking up the sheet at the other side of the same central point. Then I repeat this oper-

ation at the opposite side of the frame, and then on the other two sides of the frame. After that is done I begin taking up again where I left off, say at the right of the first point 22, and work gradually toward the corner of the frame, and repeat this operation at the left of that point 22. This operation is repeated on the opposite side of the frame and likewise on the other two sides of the frame. By this method the material is drawn evenly toward the corners of the frame and thereby avoiding the formation of wrinkles in the cloth. Sheet 3 will at this stage be drawn flat across frame 1. Sheet 4 is now adjusted to frame 2 in a similar manner. First, the sheet is grasped at opposite points 22 on either parallel sides and is drawn as taut as possible and hooked over opposite centrally located pins 21 on frame 2; then, sheet 4 is grasped at diagonally opposite points, 22, stretched taut and similarly hooked over centrally located pins. The sheet being now hooked over the frame 2 at four diametrically opposite points 22 is then hooked successively over the other pins on frame 2 and drawn evenly in the manner above described in connection with sheet 3. In this operation sheet 4 is drawn into a cone shape and gradually more stretch is given to the fabric in the same manner as sheet 3 was drawn taut until sheet 4 is drawn as evenly, without wrinkles, and as tightly as possible by hand. The fabric is then trimmed and pins 21 bent over, and strips 23 are applied to cover the edge of the fabric and the bent over pins.

In attaching sheet 4 to its frame and gradually drawing it up, a corresponding pull will be imparted to sheet 3, which thus becomes slightly dished as shown in Figure 6, and as sheet 4 is drawn up further over frame 2, the cone shape of sheet 4 gradually becomes shallower and that of sheet 3 deeper until approximately the relative proportions of Figure 7 are obtained. A final stretch is imparted simultaneously to both cones by means of the adjustable struts or braces 15 as above explained.

The fabric which I prefer to employ for diaphragms 3 and 4 is what is known as airplane cloth and after the cloth is fully stretched on the frames, either before or after facing strips 23 are applied, I coat the fabric with the waterproofing solution usually employed on airplane wings. This solution in drying draws the fabric more taut and imparts a membranous appearance thereto.

After the water proofing coating on the fabric is sufficiently dry, the electro-magnetic unit is mounted in position, and the vibrator rod 12 is inserted in pin-vise 6 and the collar screwed down to cause the vise jaws to firmly grip the rod. The sound reproducer may now be completed by applying a suitable ornamental covering around the frames to enclose the cones 3 and 4 and a grille or mesh cov-

ering may be applied over frame 2 to conceal the interior of cone 4, or the device may be enclosed in a speaker cabinet as is common practice. Such covering or cabinet arrangements being well known and forming no part of my present invention are for simplicity of illustration omitted from the drawing.

I am aware that two fabric diaphragms have been employed as the resonant body in so-called loud speakers, and my invention is designed to improve upon the construction and resonant quality of this type of sound reproducer. The resonant quality of the fabric diaphragms is improved by drawing them evenly in the manner above described whereby a cone shape is imparted to both diaphragms from apex to frame, as distinguished from merely drawing conical depressions at the centers of the diaphragms. In other words the maximum conical area is obtained and by arranging the fabric sheets so as to procure a shallow cone and a very deep cone, the range of frequencies to which the sound reproducer will respond is very materially increased, the over and under tones are more clearly brought out, and the quality and characteristics of the sounds are more accurately reproduced.

What I claim is:

1. A sound reproducer having in combination, a pair of cone-shaped fabric diaphragms, said diaphragms being joined together at the apexes of the cones, two frames between which said cones are held taut, and struts between said frames for securing same in spaced relation.

2. A sound reproducer having in combination, a pair of cone-shaped fabric diaphragms, one of greater depth than the other, and said diaphragms being joined together at the apexes of the cones, two frames between which said cones are held taut, and struts between said frames for securing same in spaced relation.

3. A sound reproducer having in combination, a pair of cone-shaped fabric diaphragms, said diaphragms being joined together at the apexes of the cones, two frames between which said cones are held taut, and adjustable struts between said frames for securing same in spaced relation and for adjusting the tension of said cones.

4. A sound reproducer having in combination, a pair of cone-shaped fabric diaphragms, one of greater depth than the other, and said diaphragms being joined together at the apexes of the cones, two frames between which said cones are held taut, and adjustable struts between said frames for securing same in spaced relation and for adjusting the tension of said cones.

5. A sound reproducer having in combination, a pair of fabric diaphragms joined together at their centers, two frames between which said diaphragms are drawn into cone

shape, the conical surfaces extending from apexes to frames, and struts between said frames for securing same in spaced relation.

6. A sound reproducer having in combination, a pair of fabric diaphragms joined together at their centers, two frames between which said diaphragms are drawn into cone shape, the conical surfaces extending from apexes to frames, and one of said cones being of greater depth than the other, and struts between said frames for securing same in spaced relation.

7. A sound reproducer having in combination, a pair of fabric diaphragms joined together at their centers, two frames between which said diaphragms are drawn into cone shape, the areas of the cone bases being the same and the conical surfaces extending from apexes to frames, and one of said cones being of greater depth than the other, and struts between said frames for securing same in spaced relation.

8. A sound reproducer having in combination, a pair of cone-shaped fabric diaphragms, a pair of stretching frames, a plurality of adjustable struts between said frames for securing the frames together in spaced relation and for stretching the diaphragms, and a connecting means securing the apexes of said cones together and for attachment to an electric speaker unit.

9. A sound reproducer having in combination, a pair of cone-shaped fabric diaphragms, one of said cones being of greater depth than the other, a pair of stretching frames, a plurality of adjustable struts between said frames for securing the frames together in spaced relation and for stretching the diaphragms, and a connecting means for securing the apexes of said cones together and for attachment to an electric speaker unit.

10. A sound reproducer having in combination, a pair of fabric diaphragms joined together at their centers, a pair of frames between which said diaphragms are drawn into cone shape, the area of the cone bases being the same and the conical surfaces extending from apexes to frames, and one of said cones being of greater depth than the other, a plurality of adjustable struts between said frames for securing the frames together in spaced relation and for stretching the diaphragms, and a connecting means for securing the apexes of said cones together and for attachment to an electric speaker unit.

11. The method of producing sound reproducer cones, consisting in securing two fabric sheets together at the centers of the sheets, stretching same between two spaced frames by first securing and stretching one sheet taut and flat while the other remains loose, then stretching and securing the second sheet and gradually increasing the ten-

sion thereby drawing the first sheet into a shallow cone.

12. The method of producing sound reproducer cones, consisting in securing two fabric sheets together at the centers of the sheets, stretching same between two spaced frames by first securing and stretching one sheet taut and flat while the other remains loose, then stretching and securing the second sheet and gradually increasing the tension thereby drawing the first sheet into a shallow cone, and finally stretching both cones by applying pressure between said frames.

13. The method of producing sound reproducer cones, consisting in securing two fabric sheets, one larger than the other, together at the centers of the sheets, stretching same between two spaced frames by first securing and stretching the smaller sheet taut and flat while the larger sheet remains loose, then stretching and securing the second sheet forming same into a deep cone, gradually taking up said sheet step-by-step around its frame thereby increasing its tension, reducing the depth of the cone and drawing the first sheet into a shallow cone, finally stretching both cones by applying pressure between said frames, and then applying a waterproofing solution to said cones.

14. This specification signed at New York city, in the county and State of New York, this 10th day of April, 1929.

EDWARD FREUND.
